H. HURTER,
CANE CRUSHING APPARATUS,
APPLICATION FILED MAY 16, 1919.

1,339,600.

Patented May 11, 1920.

UNITED STATES PATENT OFFICE.

HENRY HURTER, OF ST. LOUIS, MISSOURI, ASSIGNOR TO FULTON IRON WORKS COMPANY, OF ST. LOUIS, MISSOURI, A CORPORATION OF DELAWARE.

CANE-CRUSHING APPARATUS.

1,339,600.

Specification of Letters Patent. Patented May 11, 1920.

Application filed May 16, 1919. Serial No. 297,652.

To all whom it may concern:

Be it known that I, HENRY HURTER, a citizen of the United States of America, a resident of the city of St. Louis, in the State of Missouri, have invented certain new and useful Improvements in Cane-Crushing Apparatus, of which the following is a full, clear, and exact description, reference being had to the accompanying drawings, forming 10 a part of this specification.

My invention relates to improvements in cane crushing apparatus. The object sought by the invention is to grind a maximum tonnage of cane with the highest possible extraction of juice at a minimum operating cost. Prior to this invention it has been known that the juice can be more effectively expressed from the cane by operating the crushing rolls at a relatively low speed, and 15 that an increase in speed will result in a decrease in the efficiency of the apparatus. It is, however, desirable to operate the crushing or grinding rolls at the maximum speed so as to grind the maximum tonnage per 20 day.

My object is to produce a cane crushing apparatus having its crushing rolls so constructed and arranged that the desired high efficiency can be obtained while the rolls 25 are driven at a relatively high speed, thereby obtaining a maximum yield of juice while the cane is rapidly acted upon by the crushing rolls.

To accomplish both of these results at the same time, I utilize a series of crushers or mills which act successively upon the cane, and the elements of each crusher are so constructed and arranged that the cane crushed thereby is placed in a condition to be most 35 effectively acted upon by the next succeeding crusher. It will be important to note the proportions and arrangement of the crushing ribs on the different crushers about to be described, for the ribs differ from each 40 other, each crusher being provided with ribs adapted to most effectively act upon the cane delivered thereto, and also adapted to place the cane in such a condition that the next succeeding crusher will perform its function 45 most effectively. Each crusher is thus constructed and arranged to most efficiently perform the twofold function of expressing the juice while the cane is traveling at a high rate of speed, at the same time prop- 50 erly preparing the cane for the subsequent 55

crushing action at the different crushing ribs of the next succeeding crusher. To obtain this twofold function, it is necessary to construct the crushers or mills in a particular manner and to properly locate them 60 with respect to each other, for the cane must be first prepared by placing it in a condition to be most effectively acted upon by the ribs of a particular crusher, and this crusher must properly prepare the cane for the operation at the next succeeding crusher. If the cane is not properly prepared for the treatment it is to receive at a particular set of crushing ribs, the ribs cannot most effectively perform their function, and the same 70 would be true if the ribs were not properly formed to obtain the highest efficiency.

The preferred form of the invention comprises a primary crusher having crushing rolls provided with relatively large peripheral ribs whereby the mass of cane passing into the apparatus is subjected to a preliminary crushing, which prepares it for the second crusher having smaller ribs of less pitch than the ribs of the primary crusher. 75 From this second crusher the cane preferably passes to a cane mill comprising three crushing rolls with relatively small ribs of less pitch than the ribs of the second crusher, and after being acted upon by these ribs 80 the cane passes to a second mill having still finer ribs, and thence through a series of cane mills having ribs which preferably correspond approximately to the fine ribs of the second mill. The cane is thus successively 85 acted upon by a series of crushing rolls, or juice-expressing rolls, and the cane engaging ribs of each crusher between the ends of the apparatus are properly formed to perform the twofold function of treating the 90 cane with the highest efficiency and at the same time preparing the cane for the next succeeding crushing ribs.

Figure I is a diagrammatical view of a cane crushing apparatus embodying the features of this invention.

Fig. II is an enlarged fragmentary view showing the coarse crushing ribs on the rolls of the first crusher.

Fig. III is a view similar to Fig. II, drawn 105 to the same scale, and illustrating the co-operating crushing ribs on the rolls of the second crusher.

Fig. IV is a fragmentary view drawn to the scale of Figs. II and III, and showing 110

the ribs on the periphery of one of the rolls of the first mill.

Fig. V likewise illustrates the finer ribs on the rolls of the second, third, fourth and 5 fifth mills.

To illustrate the invention I have shown a succession of crushers, or mills, adapted to act upon the cane which travels through the apparatus, as indicated by arrows in 10 Fig. I. The first crusher comprises a pair of crushing rolls A provided with peripheral crushing ribs 6. These ribs are preferably V-shaped in cross section, as shown in Fig. II, and the ribs of one of the rolls A 15 preferably overlap the ribs of the other roll, the ribs of each roll being extended into the corresponding peripheral grooves formed in the other roll. The second crusher comprises a pair of crushing rolls B provided 20 with ribs 7, which correspond approximately to the shape of the ribs in the first crusher. However, the ribs 7 of the second crusher are preferably of less pitch and smaller than the ribs of the first crusher. 25 Furthermore, the coöperating ribs of the second crusher are preferably located relatively close to each other, as shown by Fig. III. The first mill comprises three coöperating rolls arranged as shown in Fig. I. C 30 designates the top roll of the first mill, D designates a lower roll, usually termed a "cane roll", and E designates a roll usually termed the "bagasse roll". Each of these rolls C, D and E is provided with peripheral crushing ribs 8 (Fig. IV), which are 35 finer than the corresponding ribs of the second crusher. The second, third, fourth and fifth mills each consist of a top roll C', a cane roll D' and a bagasse roll E', and each 40 of these rolls is provided with peripheral crushing ribs 9, shown in Fig. V, said ribs being smaller and of less pitch than the ribs of the first mill.

Actual experience has shown that the 45 greatly improved results herein pointed out can be obtained by making the crushing ribs conform to the dimensions indicated in Figs. II to V, inclusive, wherein the pitch of the ribs on the first crusher is $3\frac{1}{4}$ inches, on the second crusher $2\frac{1}{4}$ inches, on the first mill 1 inch and on the remaining mills $\frac{1}{2}$ inch. It is to be understood, however, that the invention is not limited to the use of crushing ribs of the dimensions indicated in the drawings.

The rotatable crushing rolls are provided with journals 10 adapted to be mounted in suitable bearings, but since such bearings are old and well known in the art. I do not 60 deem it necessary to illustrate them in the drawings. For the same reason I have omitted the driving mechanism and various other details ordinarily used in cane crushing apparatus.

65 The large ribs 6 of the first crusher are

adapted to mash and compress the cane passing into the apparatus, and the rotating rolls A feed the cane to the second crusher where it is acted upon by the finer ribs 7 which are properly designed to split and 70 shred the mass of compressed cane, thereby preparing the cane for the next operation at the still finer teeth 8 on the rolls of the first mill. The rolls C, D and E of this mill are separated from each other to receive 75 the large mass of cane passing from the second crusher, and the fine ribs 8 on these separated rolls can best perform their crushing and juice-expressing functions on a mass that has been subjected to a preliminary 80 treatment by the successive action of teeth 6 and 7 on the first and second crushers. After the cane has been gradually compressed, broken, split and crushed by the first and second crusher and the first mill, it 85 is in the form of a more or less compact mat, and this mat is fed to the still finer ribs 9 of the second mill. The rolls of this mill are preferably closer to each other than the corresponding rolls of the first mill, and the fine ribs 9 are designed to most effectively 90 squeeze the juice from a mat of cane in the condition of the mat passing from the first mill. In fact, I have found by actual experience that the ribs 9, formed as herein 95 shown, are far superior to the larger ribs in expressing the juice from the prepared mat of cane, and fine teeth of this kind are well adapted to perform the subsequent operations in the third, fourth and fifth mills. 100 I prefer, however, to arrange the coöperating rolls of the last mentioned mills closer to each other than the corresponding rolls of the second mill.

To fully appreciate the value of effective 105 crushing and high speed or high capacity, it should be understood that an apparatus of the kind herein disclosed is a very large structure capable of crushing more than a thousand tons of cane per day, and the particular structure herein shown has been found to possess the desired high efficiency when operated fast enough to grind 3500 tons of cane per day. This unusual combination of speed and efficiency is due to the peculiar manner in which the several crushing elements are associated with each other, so as to enable each crusher to most effectively 110 perform its own function and at the same time place the cane in condition for a correspondingly effective action at the next succeeding crushing elements.

I claim:

1. In a combined cane-crushing and juice-expressing apparatus, a primary crusher 125 comprising a pair of crushing rolls having coöperating peripheral crushing ribs, a second crusher comprising a pair of crushing rolls arranged in advance of the primary crusher to receive the cane passing there- 130

from, the rolls of said second crusher being provided with peripheral crushing ribs of less pitch than the crushing ribs of said primary crusher, and a juice-expressing mill 5 arranged in advance of said second crusher to act upon the cane passing therefrom, said juice-expressing mill being provided with juice-expressing rolls having peripheral ribs of less pitch than the ribs of said second 10 crusher.

2. In a combined cane-crushing and juice-expressing apparatus, a primary crusher comprising a pair of crushing rolls having coöperating peripheral crushing ribs formed 15 circumferentially of the rolls, a second crusher comprising a pair of crushing rolls arranged in advance of the primary crusher to receive the cane passing therefrom, the rolls of said second crusher being provided with circumferential crushing ribs of less 20 pitch than the crushing ribs of said primary crusher, and a succession of juice-expressing mills arranged in advance of said second crusher to successively act upon the cane 25 passing therefrom, each of said juice-expressing mills being provided with juice-expressing rolls having circumferential ribs of less pitch than the ribs of said second crusher.

3. A combined cane-crushing and juice-expressing apparatus comprising four preliminary sets of peripherally ribbed rolls whereby the cane is successively acted upon, the second set having finer ribs than the 35 first set, the third set having finer ribs than the second, and the fourth set having finer ribs than the third, and juice-expressing rolls to which the cane is delivered from said four preliminary sets of rolls.

4. A combined cane-crushing and juice-expressing apparatus comprising four preliminary sets of peripherally ribbed rolls whereby the cane is successively acted upon, the second set having finer ribs than the 45 first set, the third set having finer ribs than the second, and the fourth set having finer ribs than the third, and a series of peripherally ribbed juice-expressing mills to which the cane is delivered from said four preliminary sets of rolls.

5. In a combined cane-crushing and juice-

expressing apparatus, a primary crusher comprising crushing rolls having coöperating peripheral crushing ribs, a second crusher comprising crushing rolls arranged 55 in advance of the primary crusher to receive the cane passing therefrom, the rolls of said second crusher being provided with peripheral crushing ribs of less pitch than the 60 crushing ribs of said primary crusher, a juice-expressing mill arranged in advance of said second crusher to receive the cane passing therefrom, said juice-expressing mill comprising three coöperating juice-expressing rolls having peripheral ribs of less pitch than the ribs of said second crusher, and a second juice-expressing mill 65 arranged in advance of the aforesaid juice expressing mill to act upon the cane passing 70 therefrom, the rolls of said second juice-expressing mill being provided with peripheral ribs of less pitch than the ribs of the first mentioned juice-expressing mill.

6. In a combined cane-crushing and juice-expressing apparatus, a primary crusher comprising a pair of crushing rolls having coöperating peripheral crushing ribs, a second crusher comprising a pair of crushing rolls arranged in advance of the primary 80 crusher to receive the cane passing therefrom, the rolls of said second crusher being provided with peripheral crushing ribs of less pitch than the crushing ribs of said primary crusher, a juice-expressing mill arranged 85 in advance of said second crusher to receive the cane passing therefrom, said juice-expressing mill comprising three coöperating juice-expressing rolls having peripheral ribs of less pitch than the ribs of said second crusher, and a succession of three-roll juice-expressing mills arranged in advance of the aforesaid juice expressing mill to successively act upon the cane passing 90 therefrom, the rolls of said succession of juice-expressing mills being provided with peripheral ribs of less pitch than the ribs of the first mentioned juice-expressing mill.

In testimony that I claim the foregoing I 100 hereunto affix my signature.

HENRY HURTER.
